UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPGRAPHICAL MACHINE.

1,231,941.

Specification of Letters Patent.

Patented July 3, 1917.

Application filed September 8, 1915. Serial No. 49,506.

To all whom it may concern:

Be it known that I, JOHN R. ROGERS, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such for instance as the linotype machines disclosed in my previous Letters Patent Nos. 848,771 and 930,693, wherein matrices are delivered from one or another of a 15 series of magazines at will, in order that a line may be produced with the face represented by the matrices in one magazine, or with a combination of faces represented by matrices in two or more magazines, the de- 20 livery of the matrices being controlled by a movable assembling throat or switch and a series of escapement actuating devices shiftable into operative relation to any selected magazine.

25 In the machines specified, the assembling throat and escapement actuating devices are shifted from one magazine to another by hand, requiring considerable time and effort. To obviate this disadvantage, I have pro- 30 vided power-driven means, under the control of a finger key mechanism, for performing the shifting or adjusting operations de- 35 scribed, so that a change from one magazine to another may be effected by the mere de- 40 pression of a key, thus insuring greater speed in the operation of the machine and relieving the operator of much manual effort.

In the accompanying drawings, I have 45 shown my invention in preferred form and by way of example and as applied to the specific style of machine designated, but ob- 50 viously many variations and alterations therein, and in its mode of application, will be possible and still be comprised within its spirit. Generally speaking, I desire it to be understood that I do not limit myself to any specific form or embodiment, except in so far as such limitations are specified in the claims.

Referring to the drawings:

Figure 1 is a side elevation of part of a linotype machine equipped with my invention;

55 Fig. 2 is a vertical section thereof;

Fig. 3 is a front view of certain parts; Figs. 4, 5, 6 and 7 are sections taken on the lines 4—4, 5—5, 6—6, and 7—7, of Fig. 2, respectively; and

Fig. 8 is a detail.

The matrices X are stored according to font in one or the other of the magazines A, only two of which are shown herein, but of which a greater number might be employed if desired. The matrices are released from the magazines by the escapements C and are delivered by the throat or switch F into one or the other of the branches D' of the vertically channeled raceway D, whence they are carried to the assembler and composed in line. The line is then presented to the casting mechanism for the production of the slug, and the matrices are then carried upward and delivered to the font separator E, which assorts them according to font and drops them into one or the other of the tubes E' leading to the distillers E'', whereby they are separated according to character and returned through the channel entrances E''' to the proper channels of the magazine from which they started. The parts so far described, except as hereinafter pointed out, are, or may be, of substantially the same construction as set forth in the Letters Patent previously mentioned.

In the present instance, the throat or switch F is arranged to be moved in an inclined path from one magazine to the other to connect them with the corresponding branches of the raceway D, it being carried by a movable supporting frame H, provided at opposite sides with rollers H' traveling upon inclined tracks or guides H'' secured to the framework of the machine and having set screws H''' which limit the movement of the frame in either direction. Also mounted in the supporting frame H is a series of escapement operating levers C⁴, pivoted at their lower ends upon a transverse rod C⁵ and provided near their opposite ends with lips or projections C⁶ which are adapted to engage the push rods C² of one or the other of the two series of escapements C, according to the position of the frame or throat F carried thereby.

The levers C⁴ are operated by vertical rods C⁹ suitably guided in the framework and controlled in the usual way by the keyboard mechanism C¹⁰. In one position of the frame H, the rods C⁹ actuate the levers C⁴

by direct engagement with projections C^6 thereon, while in the other position of the frame, the rods actuate the levers through the medium of short arms C^7 arranged near the forward ends of the levers and pivoted upon a transverse rod C^8 attached to the frame. In effecting a change from one magazine to the other, therefore, the frame H is shifted in one direction or the other so as to locate the throat F and the escapement levers C^4 carried thereby into operative relation to the corresponding magazine.

This movement of the frame is effected by power-driven means under the control of 15 finger keys, one for each magazine, as will now be described. As shown particularly in Figs. 2 and 6, the frame H is connected at opposite sides by pin and slot connections to a pair of arms H^4 loose upon a rock shaft 20 H^5 journaled in the framework, each of the arms being connected to the shaft by means of two antagonistic springs H^{10} pulling thereon from the outer ends of an arm H^{20} fast or pinned to the rock shaft (Fig. 4) and 25 projecting from opposite sides thereof. In this way, when the shaft is rotated in one direction or the other, the arms H^4 are carried with it to shift the frame H , but they will be allowed to yield in the event of un- 30 due resistance offered by the parts and to absorb any shock which might result from their rapid or sudden operation. The tension of the forward springs is great enough to overcome or counterbalance the weight of 35 the supporting frame and its connected parts, as well as to counteract the force of the rear opposing springs, thus insuring the movements of the supporting frame in an easy and proper manner.

40 The rotation of the shaft H^5 in opposite directions is effected by a reciprocating slide or member H^a suitably guided in the framework and connected by a link H^7 to a crank arm H^6 fast to one end of the rock shaft 45 H^5 . The slide H^a is provided at its opposite ends with rubber-tired rollers H^8 eccentrically journaled thereon, as at H^9 , and over-weighted in such manner as to tend constantly to move into engagement with an 50 intermediate spur gear H^{16} secured to one of the ordinary keyboard rolls, which is constantly driven in the usual way. Normally, however, the rollers H^8 are prevented from contacting with the spur gear by spring 55 actuated angular dogs H^{10} , whose vertical arms are provided with laterally projecting pins H^{11} arranged in engagement with flattened pins H^{12} projecting laterally from the side faces of the rollers. (See particularly 60 Fig. 5). The tripping of one or the other of the dogs H^{10} , therefore, releases the corresponding roller H^8 , which then passes into engagement with the rotating gear H^{16} and thus raises or lowers the slide H^a , as the 65 case may be. This tripping of the dogs is

effected by means of two finger key levers H^{14} , one controlling the action of the upper dog H^{10} through the medium of an upright rod H^{13} , and the other controlling the lower dog through the medium of a small pivoted lever H^{15} , the arrangement of the rod H^{13} and the lever H^{15} being such that they are alternately connected to their respective dogs as the member H^a is shifted in opposite directions to effect a change from one 75 magazine to the other.

The operation of the parts will now be clear. As one or the other of the finger keys H^{14} is depressed, it trips the connected dog H^{10} and allows the corresponding roller H^8 to turn about its pivot H^9 and come into engagement with the constantly rotating gear H^{16} (see Fig. 8), which then effects the continued rotation of the roller in the same direction and thereby shifts the slide H^a upwardly or downwardly, as the case may be, to locate the throat F and the escapement actuating levers C^4 into operative relation to the magazine represented by the key actuated. As the slide H^a is thus shifted, the tripped dog H^{10} is disconnected from its finger key and then returned by its spring to normal or active position, so that when the roller H^8 completes its rotation, its flattened pin H^{12} reengages the pin H^{11} of the dog, which thus arrests and holds the roller in its original position and out of contact with the rotating gear H^{16} . This same action brings the other roller H^8 and its controlling dog H^{10} into operative relation to the other finger key, so that when it is actuated, the corresponding roller falls into contact with the rotating gear H^{16} and shifts the slide H^a in the opposite direction to locate the assembling devices in operative relation to the other magazine. In short, to select either one of the two magazines for use, it is merely necessary to depress one or the other of the finger keys H^{14} , thus dispensing with any manual effort on the part 100 of the operator and effecting a change from one magazine to the other in the least possible time. In order to hold the slide H^a in its different shifted positions, there is provided a spring actuated detent H^{18} mounted 110 in the framework and adapted to engage in one or the other of the recesses H^{17} in the edge of the slide, (Fig. 2).

In my prior Letters Patent, before mentioned, the magazines have their lower ends 120 beveled or inclined so as to stand in the same vertical plane and so as to permit the selecting throat to receive the matrices directly therefrom. In the present instance, the magazines A are arranged in staggered 125 relation and have their lower ends straight or right angular (which is the form in most general use) and out of alignment with each other so that the shiftable throat F is incapable of receiving the matrices directly 130

therefrom. For this reason, each of the magazines is provided at its lower end with a short channeled section A' having its partition A² adapted to register with the partitions F' of the throat F, (as shown in Fig. 7), so as to bridge the space between the magazines and the throat and guide the matrices in the proper manner from one to the other. The sections A' have their lower ends beveled or inclined and standing in an inclined plane extending parallel to the path of movement of the throat F, so that the latter may be shifted directly into operative relation thereto.

15 It will also be noted that the branches D' extend at different angles from the raceway D and have their upper ends terminating in an inclined plane corresponding to the path of movement of the throat F so as to receive the magazines directly therefrom, the foremost branch D' extending vertically toward the upper magazine while the rear-most branch extends rearwardly and upwardly toward the lower magazine. In order to gain access to the throat F and other interior parts, the two branches D' are pivotally connected as at D² to the framework so as to be swung forwardly and upwardly from their operative position, as shown by dotted lines in Fig. 1.

The magazines A are mounted so as to be swung upwardly at their lower ends away from the underlying assembling mechanism so that they may be withdrawn either forwardly or rearwardly from the machine. Referring particularly to Fig. 1, it will be noted that each of the magazines is mounted upon its customary base frame B, the upper one being supported in bracket arms B² projecting upwardly from the under frame, which latter is pivoted to the machine frame at or near its middle, as at B'. The two connected base frames thus constitute in effect a supporting frame wherein the magazines are removably mounted and which can be rocked or tilted about the pivot B' to permit the independent removal of the magazines.

As before stated, I have shown my improvements merely in preferred form and by way of example, and as applied to a specific style of machine, but obviously many modifications and alterations therein and in their mode of adaptation, will suggest themselves to those skilled in the art without departure from the scope of my invention.

Having thus described my invention, its construction and mode of operation, what I claim and desire to secure by Letters Patent of the United States is as follows:

1. In a typographical machine, the combination of a plurality of magazines, a movable assembling throat or switch, a plurality of finger keys, one for each magazine, and

power-driven means acting under the control of the finger keys to shift the assembling throat into operative relation to one or another of the magazines, according to the key actuated.

2. In a typographical machine, the combination of two magazines, a movable assembling throat or switch, two finger keys, one for each magazine, and power-driven means acting in response to the actuation of either key to shift the assembling throat into operative relation to the corresponding magazine.

3. In a typographical machine, the combination of a plurality of magazines each having a series of escapements, a single series of actuating devices for the escapements, finger keys, one for each magazine, and power-driven means acting in response to the actuation of one or another of the keys to shift the actuating devices into operative relation to the escapements of the corresponding magazine.

4. In a typographical machine, the combination of a plurality of magazines each having a series of escapements, a movable supporting frame carrying a single series of actuating devices for the escapements and an assembling throat or switch, finger keys, one for each magazine, and power-driven means acting in response to the actuation of one or another of the keys to shift the supporting frame into operative relation to the corresponding magazine.

5. In a typographical machine, the combination of a plurality of magazines, an assembling throat or switch to receive the matrices therefrom, one of said parts being movable relatively to the other to establish an operative relation between the assembling throat and one or another of the magazines, power-driven means for effecting the movement of said part, and a plurality of finger keys, one for each magazine, controlling the action of such means.

6. In a typographical machine, the combination of two magazines, assembling devices movable back and forth between the two, and power-driven means for effecting the movement of the assembling devices, said means comprising a constantly rotating part and a movable member connected to the assembling devices and provided with a pair of cams located on opposite sides of said rotating part and adapted to be thrown into engagement therewith alternately.

7. In a typographical machine, the combination of two magazines, and assembling devices movable back and forth between them, with power-driven means for effecting the movement of the assembling devices and comprising a constantly rotating part and a reciprocable member connected to the assembling devices and provided with a pair of cams adapted to be thrown into engage- 130

ment with said rotating part and to shift the member in opposite directions respectively, together with finger key mechanism to control the engagement of one or the other of the cams with the constantly rotating part.

8. In a typographical machine, the combination of two magazines, and assembling devices movable back and forth between them, with power-driven means for effecting the movement of the assembling devices and comprising a constantly rotating part and a reciprocable member connected to the assembling devices and provided with a pair of cams adapted to be thrown into engagement with said rotating part and to shift the member in opposite directions respectively, together with two finger keys, one for each cam, to control its engagement with the constantly rotating part.

9. In a typographical machine, the combination of two magazines, and assembling devices movable back and forth between them, with power-driven means for effecting the movement of the assembling devices and comprising a constantly rotating part, a reciprocable member connected to the assembling devices and carrying a pair of cams which respectively effect its movement in opposite directions, and a pair of finger keys controlling the action of said cams, said cams being shifted into and out of operative relation to their respective finger keys alternately by the movements of the reciprocating member.

10. In a typographical machine, the combination of a magazine, a channeled raceway into which the matrices from the magazine are discharged, an assembling throat leading to the raceway and whose entrance mouth is out of parallelism with the delivery end of the magazine, and a channeled section arranged between the magazine and assembling throat to guide the matrices from one to the other.

11. In a typographical machine, the combination of a plurality of magazines, an assembling throat movable from one to another thereof, and a relatively fixed channeled section arranged at the delivery end of each magazine to guide the matrices therefrom into the movable throat.

12. In a typographical machine, the combination of a plurality of magazines having their delivery ends out of alinement, an assembling throat movable in a straight path from one to another of the magazines, and channeled sections, one for each magazine, to carry the matrices therefrom to the throat, said sections having their delivery ends beveled or inclined and standing in a plane extending parallel to the path of movement of the assembling throat so as to coöperate directly therewith.

13. In a typographical machine, the com-

bination of a plurality of magazines arranged in staggered relation, a throat or switch to receive the matrices from the magazines and movable in an inclined path from one to another thereof, and a vertically disposed channeled raceway having fixed branches extending at different angles therefrom to conduct the matrices thereto from the movable throat or switch in any of its different positions.

14. In a typographical machine, the combination of a plurality of magazines arranged in staggered relation, a throat or switch to receive the matrices from the magazines and movable in an inclined path from one to another thereof, and a vertically disposed channeled raceway having fixed branches extending at different angles therefrom to conduct the matrices thereto from the movable throat or switch in any of its different positions, the said branches being pivotally mounted so as to be swung away from their operative position to give access to the other parts.

15. In a typographical machine, the combination of a plurality of magazines arranged in staggered relation, a throat or switch to receive the matrices from the magazines and movable in an inclined path from one to another thereof, and a vertically disposed channeled raceway having fixed branches extending at different angles therefrom to conduct the matrices thereto from the movable throat or switch in any of its different positions, the said branches being pivotally mounted at their upper ends so as to be swung upwardly away from the magazines and raceway.

16. In a typographical machine, the combination of a plurality of magazines, a vertically disposed channeled raceway having branches leading to the respective magazines, said branches having their receiving ends terminating in an inclined plane, and a throat or switch arranged between the raceway and magazines and movable in an inclined path to connect one or another of the branches with the corresponding magazine.

17. In a typographical machine, the combination of a plurality of magazines each provided with escapements, and means for actuating the escapements, said means comprising the vertically guided rods C⁹, and the intermediate pivoted levers C⁴, the latter being arranged so as to be movable in a longitudinal direction into operative relation to the escapements of one or another of the magazines and adapted to be operated by the rods in any of their different positions.

18. In a typographical machine, the combination of a plurality of magazines, assembling devices, a movable supporting frame therefor, and means for moving said supporting frame to locate the assembling de-

vices in operative relation to one or another of the magazines, the said means including a part connected to the supporting frame and shiftable in opposite directions in effecting its movements, and a pair of antagonistic springs tending to move said shiftable part in the said opposite directions.

19. In a typographical machine, the combination of a plurality of magazines, assembling devices, a movable supporting frame therefor, and means for moving said supporting frame to locate the assembling devices in operative relation to one or another of the magazines, the said means including a part connected to the supporting frame and shiftable in opposite directions in effecting its movements, and a pair of antagonistic springs tending to move said shiftable part in the opposite directions, one of said springs being stronger than the other so as to counterbalance the weight of the supporting frame and its connected parts.

20. In a typographical machine, the combination of a plurality of magazines, assembling devices, means for moving the assembling devices in opposite directions to bring them into operative relation to one or another of the magazines, said means including the pivoted lever H^4 connected to the assembling devices, the rock shaft H^5 whereon the lever is loosely mounted, the arm H^{20} fixed to the rock shaft, and the springs H^{19}

connected to the lever and pulling from the outer ends of the arm H^{20} , for the purpose described.

35

21. In a typographical machine, the combination of a plurality of magazines each having a series of escapements, and means for operating the escapements of the several magazines, said means including a series of operating devices, and an intermediate series of inclined actuating members movable in a longitudinal direction into operative relation to the escapements of one or another of the magazines and adapted to maintain their connection with the operating devices in any of its different positions.

40

22. In a typographical machine, the combination of a plurality of magazines each having a series of escapements, and means for operating the escapements of the several magazines, said means including a series of operating devices, and an intermediate series of inclined actuating members movable in a longitudinal direction into operative relation to the escapements of one or another of the magazines, the said members being pivoted at their lower ends and adapted to be engaged by the operating devices in advance of their pivots in any of their different positions.
